UNITED STATES PATENT OFFICE.

WILLIAM HARVEY PARSONS, OF MIDDLETOWN, CALIFORNIA.

ORE-FEEDING APPARATUS.

Application filed October 18, 1926. Serial No. 142,481.

This invention relates to ore-feeding apparatus particularly designed for automatically feeding ore to a rotary ore furnace.

An object of the invention is to provide 5 a more positive apparatus for supplying and feeding ore to the rotating drum of an ore furnace, together with means for preventing over-feeding of the ore by temporarily rendering the feeding mechanism inactive.

10 More specifically, the invention comprehends a feed trough communicating with the hopper, in which means is provided for advancing the ore in the trough toward its discharge end, which means is actuated in 15 such a manner as to prevent retrograde movement of the ore in the trough.

As a still further object, the invention resides in the provision of an ore-feeding mechanism which is comparatively simple 20 in its construction and mode of operation, which is highly efficient in its purpose, and comparatively inexpensive to produce and install.

With the above recited and other objects 25 in view, reference is had to the following specification and accompanying drawings in which there is exhibited one example or embodiment of the invention which is in no way intended as a limitation upon the scope 30 of the appended claims as it is to be clearly understood that variations and modifications which properly fall within the scope of said claims may be resorted to when found expedient.

35 In the drawings—

Figure 1 is a fragmentary sectional view 40 through a furnace equipped with an ore-feeding mechanism constructed in accordance with the invention and taken approximately on the line 1—1 of Fig. 3;

Fig. 2 is a similar view taken approximately on the line 2—2 of Fig. 3;

Fig. 3 is a fragmentary sectional plan view;

Fig. 4 is a transverse sectional view taken approximately on the line 4—4 of Fig. 1;

Fig. 5 is a similar view taken approximately on the line 5—5 of Fig. 1.

50 Referring to the drawings by characters of reference, 10 designates a furnace wall through which the upper receiving end of a rotary furnace drum 11 protrudes. A vertical wall 12 spaced from the furnace wall 10 defines a dust chamber 13 therebetween.

55 The ore-supply and feeding mechanism includes a chute 14 suitably supported by a

table 15, the chute extending through the dust chamber and communicating with the lower end of a hopper 16 to which the ore is initially supplied. The chute is of substantially channel shape in cross-section and is provided at its discharge end with a gravitationally closed door or gate 17, the said lower end extending into the upper receiving end of the rotary furnace drum 11.

In order to provide means for advancing or pushing the ore received from the hopper to positively feed the same through the gravitationally closed gate 17, a feeder arm 18 is provided having feeder blades 19 projecting laterally therefrom. The feeder arm extends through a bearing 20 in the rear or outer end wall 21 of the trough and has pivotally connected thereto at its outer end a gravity latch 22 formed with a coupling notch 23 which normally engages the free terminal 24 of a rock lever 25 fulcrumed at 26 to the table 15. Rocking motion is imparted to the rock lever by means of a pitman or connecting rod 27 pivoted at one end as at 28, to the opposite end of the rock lever 25. The opposite end of the pitman or connecting rod is operatively connected to an eccentric or crank pin 29 on a driven pulley 30.

In order to effect a lifting or elevation of the feeder blades 19 upon rearward or outward movement of the same so as to prevent retrograde movement of the ore in the trough, a ramp plate 31 is fulcrumed at 32 to a bracket 33 on the table 15, and said ramp plate presents an upwardly and rearwardly or outwardly inclining upper surface 34. A roller 35 is mounted on a radially disposed arm 36 at the rear or outer end of the feed arm 18 and coacts with the upper surface 34 of the ramp plate upon rearward movement of the arm 18 to turn said arm in the bearing 20 during its rearward movement so as to lift or elevate the blades 19 above the level of the ore in the trough. The ramp plate 31 is normally swung downwardly by gravity so that its free end 37 contacts with the upper face of the table 15. As the arm 18 reaches the rearward limit of its movement the roller 35 drops from the ramp plate on to the upper face of the table so that the blades 19 again contact with the bottom of the trough, and upon forward movement the arm causes the roller to pass under the ramp plate onto the upper face of the table so that the blades 19 can con-

100
105
110

tact with the bottom of the trough and upon forward movement the arm causes the roller to pass under the ramp plate and lift the same until it clears the free end 37 allowing 5 the ramp plate to again gravitate to its normal position.

In order to provide means for preventing an overfeeding of the ore to the furnace drum, a gravitationally closed gate or door 10 17 has connected therewith at its fulcrum a crank arm 38 which is connected by a rod 39 to a trip lever 40 fulcrumed at 41 on the table 15. The gravity latch 22 is provided with a trip lug 42 which is designed to engage 15 with the terminal 43 of the trip lever 40 when said lever is shifted rearwardly so as to swing the free outer end or nose 44 of the latch upwardly and disengage the coupling notch 23 from the free terminal of 20 the rock lever 25. The trip lever 40 is swung rearwardly when an excessive quantity of ore has been advanced against the gravitationally closed gate 17 so that the gate is lifted a predetermined distance thereby 25 shifting the rod 39 rearwardly. This throws the feeder arm and blades out of operation until the congested condition of the ore in the upper end of the furnace drum permits the door 17 to gravitate downwardly again 30 pulling the trip lever forward from the engagement of its terminal 43 with the lug 42. The gravity latch will then swing downwardly to its normal position so that the next forward movement of the terminal 24 35 of the rock lever 25 will engage the cam surface 45 of the nose 44 of the gravity latch and reenter the coupling notch 23, thereby coupling the feeder arm 18 with the rock lever for a continuance of the feeding operation.

In operation, the ore supplied to the hopper 16 gravitates into the trough 14, the reciprocating movement of the feeder arm 18 functioning to cause upon each forward 45 or inward movement an advancement of the ore through the trough and into the upper end of the furnace drum 11. The rearward movement of the feeder arm, as heretofore described, causes a lifting or elevation of the 50 blades 19 so as to prevent retrograde or rearward movement of the ore in the bottom of the trough. In event of excessive feeding of the ore through the trough to the furnace drum, or, in other words, where 55 the furnace drum does not take off the ore as fast as it is fed, it is obvious that the ore will become congested adjacent the gravity door 17 and will raise or lift the same to substantially the dotted line position 60 of the door illustrated in Fig. 2. When the door is raised or lifted to this point, the crank 38 will shift the rod 39 rearwardly and swing the trip lever 40 to the position illustrated in dotted lines in Fig. 3. In this 65 position, the terminal 43 of the trip lever is

disposed in the path of movement of the lug 42 of the gravity latch 22. This effects a lifting of the gravity latch to a position which will cause the nose 44 to be elevated above the terminal 24 of the rock lever 25 so 70 that the rock lever will be disconnected or uncoupled from the feeder arm 18. This renders the feeding mechanism inactive until the congested or clogged condition at the outlet end of the trough is relieved, at which 75 time the gate or door 17 will gravitate to a normal position shifting the trip lever 40 forward or inward from its engagement with the lug 42 of the latch, allowing recoupling of the rock lever 25 with the feeder 80 arm 18.

What I claim is:

1. An apparatus for feeding materials through a trough from the receiving end to the discharge end thereof, comprising a reciprocatory feed arm arranged in the trough having radially disposed feed blades secured thereto, and means for turning the feed arm to elevate the blades upon each movement of the same from the discharge end to the receiving end whereby to prevent retrograde movement of the material in the trough. 85

2. An apparatus for feeding materials through a trough from the receiving end to the discharge end thereof, comprising a reciprocatory feed arm arranged in the trough having radially disposed feed blades, and means for turning the feed arm to elevate the blades upon each movement of the same from the discharge end to the receiving end whereby to prevent retrograde movement of the material in the trough, said apparatus including continuously driven actuating means detachably connected with the feed arm and mechanism for disconnecting the feed arm from the actuating means upon excessive feeding of the material to the discharge end of the trough. 95

3. In an apparatus for supplying ore to a rotary furnace drum, a chute having its discharge end extending into the furnace drum, an ore hopper communicating with the opposite end of the chute, and mechanism for feeding the ore through the chute from the hopper to the discharge end, said mechanism including a feeder arm arranged for reciprocatory movement in the bottom and at one side of the chute, laterally projecting feeder blades on the arm, a driven rock lever, a gravity latch carried by the feeder arm normally engaging the free terminal of the rock lever, and means operable upon rearward movement of the feeder arm for operating the same to swing and elevate the feeder blades for preventing retrograde feeding of the ore. 110

4. In an apparatus for supplying ore to a rotary furnace drum, a chute having its discharge end extending into the furnace drum, an ore hopper communicating with the op- 130

posite end of the chute, and mechanism for feeding the ore through the chute from the hopper to the discharge end, said mechanism including a feeder arm arranged for reciprocatory movement in the bottom and at one side of the chute, laterally projecting feeder blades on the arm, a driven rock lever, a gravity latch carried by the feeder arm normally engaging the free terminal of the rock lever, and means operable upon rearward movement of the feeder arm for operating the same to swing and elevate the feeder blades for preventing retrograde feeding of the ore, said means consisting of a laterally projecting shaft on the feeder arm, a roller on said shaft, and a pivoted gravity ramp plate disposed in the path of movement of said roller.

5. In an apparatus for supplying ore to a rotary furnace drum, a chute having its discharge end extending into the furnace drum, an ore hopper communicating with the opposite end of the chute, and mechanism for feeding the ore through the chute from the hopper to the discharge end, said mechanism including a feeder arm arranged for reciprocatory movement in the bottom and at one side of the chute, laterally projecting feeder blades on the arm, a driven rock lever, a gravity latch carried by the feeder arm normally engaging the free terminal of the rock lever, and means operable upon rearward movement of the feeder arm for operating the same to swing and elevate the feeder blades for preventing retrograde feeding of the ore, said means consisting of a laterally projecting shaft on the feeder arm, a roller on said shaft, a pivoted gravity ramp plate disposed in the path of movement of said roller,

plate disposed in the path of movement of said roller, and means for swinging the gravity latch to a position for disconnecting the feeder arm from the rock lever upon feeding of the ore to the furnace drum in excess of its capacity.

6. In an apparatus for supplying ore to a rotary furnace drum, a chute having its discharge end extending into the furnace drum, an ore hopper communicating with the opposite end of the chute, and mechanism for feeding the ore through the chute from the hopper to the discharge end, said mechanism including a feeder arm arranged for reciprocatory movement in the bottom and at one side of the chute, laterally projecting feeder blades on the arm, a driven rock lever, a gravity latch carried by the feeder arm for operating the same to swing and elevate the feeder blades for preventing retrograde feeding of the ore, said means consisting of a laterally projecting shaft on the feeder arm, a roller on said shaft, a pivoted gravity ramp plate disposed in the path of movement of said roller, and means for swinging the gravity latch to a position for disconnecting the feeder arm from the rock lever upon feeding of the ore to the furnace drum in excess of its capacity, said last-mentioned means comprising a gravity door at the discharge end of the chute swingable to a predetermined position upon over-feeding and a trip lever connected thereby movable into the path of movement of the gravity latch for elevating the same to disengage the rock lever.
